Inventor:
Silas Edgar Trout.

By *Frank A. Kane*, Attorney

UNITED STATES PATENT OFFICE.

SILAS EDGAR TROUT, OF PHILADELPHIA, PENNSYLVANIA.

CARD INDEX.

Application filed July 27, 1922. Serial No. 577,882.

REISSUED

To all whom it may concern:

Be it known that I, SILAS EDGAR TROUT, a citizen of the United States, residing at Philadelphia, Pennsylvania, have invented 60
5 certain new and useful Improvements in a Card Index, of which the following is a specification, reference being had therein to the accompanying drawing.

This invention comprises a card index. 10 It is contemplated to provide certain improvements in devices of this kind, particularly where a number of overlapping cards are arranged in a frame or carrier in such a way that only a line or small portion 15 of each card is exposed.

In the present invention a holder for the cards or pocket is formed by the simple expedient of arranging a member on the lower portion of a flat card, at either end thereof, 20 the card-pocket itself being suspended by ordinary paper clips on the looped ends of a fine wire, in such a manner that slight bending of the card will permit its removal, and the wire itself being movably or pivotally mounted in bails or eyes upon a backing strip of metal or the like which strip has end portions slidably arranged in and supported by turned-over portions of the carrying frame. 25

30 More specific objects and advantages will be brought out more fully in the description which follows.

A drawing illustrating an embodiment of the invention accompanies the specification, 35 the following views being shown:

Fig. 1, is a fragmentary view in front elevation of a frame or carrier with several card-carrying devices arranged therein;

Fig. 2, is a view in top plan, the frame 40 being shown in section;

Fig. 3, is a detail view on line 3-3 of Fig. 1;

Figs. 4, 5, and 6, are fragmentary detail views in elevation of three modified card-carrying devices. 45

In these views 1 indicates a frame or carrier, having bent-over edges 2 which form a bearing and support for a flat plate or strip 3 removably insertable under the bent-over portions and between these and the body of the frame.

This strip is preferably resilient so as to be capable of being bowed in the centre in addition to the manner of inserting by sliding the ends under the bent-over portions of the frame. It has at opposite ends, and at

a point spaced from the bent edges of the frame, when inserted, bails or eyes 4. These are preferably stamped up from the body of the strip and constitute bearings in which a wire or the like 5 is mounted. The ends of this wire are bent inwardly and in spaced relation to the eyes, forming bearings upon which clips 6 may be pivotally arranged.

These clips are secured to a card 7, at 65 either side thereof, the card 7 being of resilient material so that by slightly bowing it centrally the clips may be removed from or inserted upon the turned-over portions of the wire. The card 7 is also provided with 70 card-carrying means so as to constitute a pocket or support for a card or the like 8.

As here shown there are several alternative means provided. In Fig. 1 is shown a form wherein a piece of material, preferably transparent, is extended diagonally across the corner edges of a card, one on each end of the card, the ends of each strip being secured to the back of the card. In Fig. 4, is shown a form wherein a piece of material, preferably transparent, has a portion 9 arranged in spaced relation to the face of card 7, and a portion bent back around the edge of card 7 and secured to the back thereof as by pasting. 75 80 85

In Figs. 5 and 6, pockets or carriers are formed by providing slits 10 in the face of the card and at an angle to each other. A strip 11 of preferably transparent material such as oiled silk or the like is extended between the slits, end portions 12 of this strip being passed through the slits and secured to the back of the card 7. In Fig. 6, one end of strip 11 is passed through a slit and the other end passed over the edge of the card 90 and secured to the back in any suitable manner, usually by pasting.

The provision of the bails in the resilient strip with the wire inserted, constitutes a cheap, easily made and very effective manner of mounting card carriers. The use of a wire in the bails and provided with bent-over ends to constitute carriers for the card clips, permits more easy inspection and turning of the card carriers as they are pivotally mounted on the ends of the wires and may be inserted and removed by merely bending the cards. It also assures a better lay of the cards and carriers than is afforded where only a bent portion of wire is depended upon 105 for this purpose. 110

The arrangement of pockets in the carry-

ing cards also simplifies this construction, reducing weight and adding to simplicity and efficiency.

It will be understood that certain obvious changes in arrangement and construction are considered within the scope of the invention as claimed.

What I claim is:

A card index comprising a carrying frame 10 having flanged portions constituting a bearing and support for card-carrying strips; a strip having ends adapted to be disposed

under the flanged portions of the frame; bails disposed on said strip and constituting bearings for a card-carrying member; a 15 card-carrying member mounted on said bails, said member having portions extending in spaced relation to the body thereof; a card-carrying clip adapted to pivotally bear on a portion of the card-carrying member; and 20 a card-carrying support adapted to be attached to the clip.

In testimony whereof I affix my signature.
SILAS EDGAR TROUT.
